United States Patent

Des. 235,470
Patented June 17, 1975

235,470

COMBINED READING AND EXAMINATION LIGHT AND SUPPORT THEREFOR

Mitchell Bobrick, Redondo Beach, and Mel Evenson,
Santa Monica, Calif., and Morris M. Buzan, St. Charles,
and Murray L. Quin, St. Louis, Mo.; said Buzan and
Quin assignors to Emerson Electric Co.

Filed July 5, 1973, Ser. No. 376,542

Term of patent 14 years

Int. Cl. D26—05

U.S. Cl. D48—20 H

Fig. 3

Fig. 2

Fig. 1

FIG. 1 is a perspective view of a combined reading and examination light and support therefor showing our new design;

FIG. 2 is a rear perspective view of the light, the support being omitted for convenience of illustration;

FIG. 3 is a side elevational view of the carriage, the boom and light being omitted for convenience of illustration; the opposite side of the carriage is a mirror image.

The top of the light casing is flat and unornamented except for the narrow channel which gives the effect of striping on the rear edge. The rail upon which the carriage travels is shown in broken lines in FIGS. 1 and 3 for illustrative purposes only.

We claim:

The ornamental design for a combined reading and examination light and support therefor, as shown and described.
